UNITED STATES PATENT OFFICE.

SAMUEL SMITH YOUNGHUSBAND, OF DARLINGTON, ENGLAND.

SLIDE-VALVE GEAR.

SPECIFICATION forming part of Letters Patent No. 703,885, dated July 1, 1902.

Application filed September 4, 1901. Serial No. 74,272. (No model.)

To all whom it may concern:

Be it known that I, SAMUEL SMITH YOUNGHUSBAND, engineer, a subject of the King of Great Britain, residing at Granville Terrace, 5 Woodlands Road, Darlington, in the county of Durham, England, have invented new and useful Improvements in Slide-Valve Gear for Steam-Engines, of which the following is a specification.

My invention relates to valve-gear of locomotive-engines having coupled driving-wheels, inside cylinders, and outside valve-chests; and it consists of a special construction of eccentric sheave and stud for working the expansion or reversing link of the valve-gear.

In the drawings, Figure 1 is a side elevation, and Fig. 2 a part-sectional plan, drawn to a smaller scale, of the valve-gear, in which the expansion and reversing link is actuated by an eccentric sheave and stud in combination with the coupling-rod crank-pin of a locomotive having coupled drivers, inside cylinders, and outside valve-chests. Fig. 3 is a sectional detail view of the eccentrics shown in Figs. 1 and 2. Fig. 4 is a slight modification of the eccentrics shown in Figs. 2 and 3. Figs. 3 and 4 are drawn to a larger scale.

The present invention is illustrated as applied to work a valve-gear in which motion is transmitted from the reversing or expansion link to the slide-valve through an intermediate lever having a pivotal connection with the die-block of the link, the said lever being connected by its shorter arm to the valve-rod and suspended by its other arm from an arm or arms on the weigh-shaft and in which the connection with the expansion-link of the link-suspension device and of the rods of the forward and backward eccentrics is effected by means of gudgeons carried by a pair of cheek-plates fixed to the expansion-link at either side thereof and at a distance therefrom, as described in the specification of another application for Letters Patent, No. 61,240, filed May 21, 1901.

In the drawings, A is the frame-plate; A', the cylinder; A², the valve-chest; B, one of the driving-wheels; B', the other driving-wheel, coupled to B; C, the axle of wheel B; D, the driving-wheel coupling-rod; c, the

driving-crank on axle C; c', connecting-rod; c², piston-rod, and a b are the centers of the forward and backward eccentrics, respectively. 55

d is the reversing or expansion link, and e e the cheek-plates fixed thereto by bolts f and distance-pieces, provided with gudgeons g for the carrier-links h, pivoted at i, and 60 gudgeons j l for the connection of the forked ends of the forward and backward eccentric- rods k m, respectively.

n is the die-block, fitted in the slot of link d; p, the intermediate lever coupled to the 65 die-block at o, fulcrumed at q to the arms r of weigh-shaft s, the short arm of lever p extending beyond the die-block and being connected at t to valve-rod u, which is pivoted at u' to the slide-valve spindle u². 70

Motion is transmitted to the link d through rods k m, respectively, from a sheave v, eccentric to the wheel-axle, and from a stud w, formed on sheave v eccentrically as regards both the said sheave v and the wheel-axle, 75 the eccentric sheave v being carried by a return crank-arm z and all being made in one with the coupling-rod crank-pin x. The strap k' of rod k is secured on the sheave v through the medium of a liner-ring y, made in segments and fitting in the grooved periphery of sheave v at the same time that a circumferential rib on the liner fits in a groove in the strap, so that the liner makes a shouldered connection with both the sheave and strap. 80 The eye m' of the rod m is secured on stud w by a nut w'. 85

In Fig. 4 the stud w and the eye m' of the rod m are recessed into the face of the eccentric sheave v. 90

Having thus described my invention, what I claim as new, and desire to secure by Letters Patent, is—

1. In a locomotive-engine having coupled driving-wheels, inside cylinders and outside valve-chests, the combination with the link-motion and with the coupling-rod shank-pin, of a link-operating mechanism consisting of a sheave eccentric to the wheel-axle, and a stud eccentric both to the sheave and wheel-axle, said stud and sheave being formed in one with a return crank-arm and with the coupling-rod crank-pin, substantially as specified. 95 100

2. In a locomotive-engine of the class described, the combination with the link-motion, and the driving-wheel coupling-rod, of a link-operating mechanism consisting of an eccentric carried by the coupling-rod crank-pin and provided with a stud eccentric thereto, as set forth.

3. In a locomotive-engine of the class described, the combination with the link-motion, and the driving-wheel coupling-rod, of a link-

operating mechanism consisting of an eccentric provided on one face with a crank-arm secured to the coupling-rod crank-pin, and on its other face with a stud projecting eccentrically therefrom, as set forth.

SAMUEL SMITH YOUNGHUSBAND.
